UNITED STATES PATENT OFFICE.

HARRY KLEIN, OF FREEPORT, NEW YORK.

LAMP-SECURING MEANS.

1,384,961.

Specification of Letters Patent. Patented July 19, 1921.

Application filed November 3, 1919. Serial No. 335,313.

To all whom it may concern:

Be it known that I, HARRY KLEIN, a citizen of the United States, and resident of Freeport, in the State of New York, have 5 invented certain new and useful Lamp-Securing Means, of which the following is a specification, the same being a full, clear, and exact description of the invention, such as will enable others skilled in the art to 10 which it appertains to make and use the same.

This invention relates to key controlled fastening means, and in particular to locking devices for lamps, as an appliance for 15 securing in position an incandescent lamp within its socket, and its object is to provide such a device of this character as shall prevent unauthorized withdrawal of the lamp, the invention also comprising a lamp of improved construction and a socket to properly 20 coact with the same.

In order to attain the said object and other desirable features and objects which will be hereinafter set forth, the invention 25 consists in the construction, arrangement and operation of parts described below.

In the drawings, illustrative of one embodiment of the invention, which accompany and form a part of this specification,

30 Figure 1 represents an elevation of an article constructed according to my invention;

Fig. 2 is a transverse section of the socket taken in a vertical plane and showing my 35 locking device;

Fig. 3 is an elevation of the upper part of the lamp illustrating my closure ring; and

Fig. 4 is a plan view looking upward from 40 the line 4-4, Fig. 1, showing the engagement of the screw with the socket.

Referring particularly to the drawings, the numeral 1 denotes my lamp having an eccentrically located neck 2, around which 45 neck is positioned a tube or band 4 concentric with the longitudinal axis of the body of the lamp, which band is constructed and arranged to surround the neck of the lamp and to be spaced at one side from the latter.

50 The said band has an interiorly disposed bearing 6 for a screw 7 and also an orifice 8 adapted to register with the head of the screw and to serve as a key hole for the entrance therethrough of a suitable key. The 55 upwardly and angularly inclined screw has a head portion comprising projecting and

recessed portions 10 adapted to be engaged by a key of correspondingly reversed conformation, and at the other end of the said key a point is located constructed and arranged to become interlocked with one of the convolutions at the lower part of the socket at will, the lower edge of the said socket 3 being preferably arranged so as to not entirely cover the closure ring 5 which 60 surrounds the band 4 and is rotatable thereon, and it may have a knurled edge and also an orifice 9 adapted to be registered with, or removed from, the first named orifice 8 of the band 4, the said closure thus serving to 65 form a cover for the orifice 8 in order to normally conceal the said key hole.

The said bearing 6 and screw 7 are located within the contour of the band 4 and the screw is supported at the base of the lamp 70 in the space provided at one side thereof on account of the eccentric formation of the neck of the lamp. The lower part of the band 4 is preferably shaped so as to bear against the body of the lamp and thus conceal the eccentric position of the neck thereof, thus enabling the lamp—which is made with a central stem—to have a symmetrical appearance and to resemble in conformation that of an ordinary lamp. 75

The lamp may be secured in the socket in the ordinary manner, and then, by rotating the ring 5 so that the orifices 8 and 9 will register with each other, and applying a proper key to the head 10 of the screw 7, the 80 latter will be caused to work in its bearing 6 until the point of the screw engages the inner face of one of the convolutions of the screw shell of the socket, the spiral conformation of which will prevent any rotation of the lamp by the engagement with the said convolution by the screw carried by the lamp, in consequence of which, the lamp can not be withdrawn until a suitable key is 85 again inserted in the orifice 8 and the screw 100 7 thereby unscrewed once more so to release the latter from the socket, whereupon the lamp will be free to turn and to be withdrawn.

A key will be furnished to any one authorized to remove a lamp from its socket, the said key being of a size to enter the key hole or orifice 8, and constructed and arranged to interlock or intermesh with the projections and recessed portions of the head 105 of the screw, so that, upon the application of the key and the manipulation of the same,

the point of the screw may be withdrawn from the socket of the lamp and the latter removed. When it is desired to insert a lamp in the socket, an operation reverse 5 from that described will have to be performed, as will be readily understood.

The head of the locking screw is normally concealed by the closure ring 5 in order to tend to prevent tampering with the 10 device, and it will be necessary, in either inserting or removing a lamp, to rotate the said ring so that its orifice 9 will register with the orifice 8 of the band 4, the said closing of the orifice or key hole 8 serving to 15 give the lamp a more finished appearance.

I wish it to be understood that I do not desire to be limited to the particular use or the exact details of construction shown and described, for obvious modifications will occur to persons skilled in the art.

What I claim as my invention is:—

1. In a device of the class described, a socket, a lamp having the neck thereof arranged eccentrically to the axis of the lamp 25 to provide a space at one side of said neck and between the latter and the socket, and a locking device arranged in said space.

2. In a device of the class described, a socket, a lamp having the neck thereof arranged eccentrically to the axis of the lamp 30 to provide a space at one side thereof and between the latter and the socket, a concentric band encircling the neck, and a locking device arranged in said space.

3. In a device of the class described, a socket, a lamp having the neck thereof arranged eccentrically to the axis of the lamp 35 to provide a space at one side of said neck and between the latter and the socket, a concentric band encircling the neck and provided with a peripheral orifice, and a locking device comprising a screw arranged in 40 said space and adapted to register with said orifice.

4. In a device of the class described, a socket, a lamp having the neck thereof arranged eccentrically to the axis of the lamp 45 to provide a space at one side of said neck and between the latter and the socket, a concentric band encircling the neck and provided with a peripheral orifice, and a locking device comprising an upwardly and angularly inclined screw arranged in 50 said space and adapted to register with the orifice.

5. In a device of the class described, a socket, a lamp having the neck thereof arranged eccentrically to the axis of the lamp 55 to provide a space at one side of said neck and between the latter and the socket, a concentric band encircling the neck and provided with a peripheral orifice, and a lock-

ing device comprising an upwardly inclined screw arranged in said space and adapted to register with said orifice and to be engaged with the socket at will. 65

6. In a device of the class described, a socket, a lamp having the neck thereof arranged eccentrically to the axis of the lamp to provide a space at one side of said neck 70 and between the latter and the socket, a concentric band encircling the neck and provided with a peripheral orifice, and a locking device comprising a key controlled screw arranged in said space and adapted to register with said orifice. 75

7. In a device of the class described, a socket, a lamp having the neck thereof arranged eccentrically to the axis of the lamp to provide a space at one side of said neck 80 and between the latter and the socket, and a locking device arranged in said space comprising an upwardly inclined screw.

8. In a device of the class described, a socket, a lamp having the neck thereof arranged eccentrically to the axis of the lamp to provide a space at one side of said neck 85 and between the latter and the socket, a concentric band encircling the neck and provided with a bearing, and a screw arranged in said space and adapted to work in said bearing.

9. In a device of the class described, a socket, a lamp, a bearing for a screw, and a screw having a head comprising projecting 95 and recessed portions at one end and a point at the other extremity adapted to engage the socket, and a band having an orifice, also a ring closure encircling the said band also having an orifice adapted to be registered with or removed from the first named orifice at will. 100

10. In a device of the class described, a socket having a screw shell, an incandescent lamp having a base to engage therewith, a band or tube around the neck of the lamp 105 and spaced at one side from the latter, and having an orifice, a screw contained in said space and adapted to register with the orifice, and a closure for the said orifice. 110

11. In a device of the class described, a socket, a lamp having a base, a movable band encircling but spaced from the said base, and locking means positioned intermediate the base and band and adapted to engage the socket. 115

12. In a device of the class described, a socket, a lamp having a base, a movable band encircling but spaced from the said base, and locking means positioned intermediate the base and band and adapted to engage the socket, the said band having an orifice to register with the locking means. 120

HARRY KLEIN.
